CHLORINATOR UNIT FOR SWIMMING POOLS OR THE LIKE

Wesley V. Bates and Bobby L. Bates, San Dimas, Calif.,
assignors to Jacketing Specialty, a corporation of
California

Filed Aug. 1, 1968, Ser. No. 12,995

Term of patent 14 years

Int. Cl. D23—01

U.S. Cl. D23—3

FIG. 1.

FIG. 6.

FIG. 4.

FIG. 2.

FIG. 3.

FIG. 5.

FIG. 1 is a front, perspective view of our new chlorinator unit for swimming pools or the like design;

FIG. 2 is a rear perspective view thereof;

FIG. 3 is a side elevation view thereof;

FIG. 4 is a top plan view thereof;

FIG. 5 is a bottom view thereof; and

FIG. 6 is a sectional view taken on line 6—6 of FIG. 1.

The dominant features of our design reside in the portion shown in full lines only.

We claim:

The ornamental design for a chlorinator unit for swimming pools or the like, substantially as shown and described.
